DESIGN FOR A DRESS ENSEMBLE

Tora Coleman, New York, N. Y.

Application April 8, 1938, Serial No. 76,366

Term of patent 3½ years

To all whom it may concern:

Be it known that I, Tora Coleman, a citizen of Latvia, residing in the city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble, showing my new design.

Fig. 2 is a rear view thereof.

Fig. 3 is a fragmentary front view of the dress member of the ensemble.

Fig. 4 is a rear view of Figure 3.

I claim:

The ornamental design for a dress ensemble substantially as shown.

TORA COLEMAN.
